(57) **CLAIM**

The ornamental design for a lightning rod support base, as shown and described.

DESCRIPTION

FIG. 1 is a first perspective view of a lightning rod support base showing a new design;

FIG. 2 is a second perspective view of the lightning rod support base;

FIG. 3 is a top plan view of the lightning rod support base; FIG. 4 is a bottom plan view of the lightning rod support base;

FIG. 5 is a first perspective view of another embodiment of the lightning rod support base showing;

FIG. 6 is a second perspective view of the lightning rod support base;

FIG. 7 is a top plan view of the lightning rod support base; and,

FIG. 8 is a bottom plan view of the lightning rod support base.

In the drawings the dash-dash broken lines are for the purpose of illustrating environment only and form no part of the claimed design.
